SMOKER'S APPLIANCE

Hugh T. Kirkland, Charles H. Sapper, Hyman B. Lasting, and Joseph Elkin, Portsmouth, Va., assignors to Pressed Metals Commodities, Inc., Portsmouth, Va., a corporation of Virginia

Application April 2, 1934, Serial No. 718,708

4 Claims. (Cl. 131—51)

The present invention relates to new and useful improvements in smokers' appliances and has for its primary object to provide, in a manner as hereinafter set forth, an ash tray or receiver embodying novel means for convenient attachment to a card table or other support.

Another very important object of the invention is to provide an appliance of the aforementioned character which comprises in a single article an ash tray or receiver, a cigarette holder and a match holder.

Still another very important object of the invention is to provide an appliance of the character described embodying a novel construction whereby the ash tray may be conveniently removed from its attaching and supporting means for emptying.

Other objects of the invention are to provide a smoker's appliance of the character set forth which will be comparatively simple in construction, strong durable, highly efficient and reliable in use, compact, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

Figure 1 is a view in side elevation of a smoker's appliance constructed in accordance with the present invention, showing the same attached to a card table.

Figure 2 is a view in front elevation thereof.

Figure 3 is a side elevational view of the device, showing the same mounted on another type of table.

Figure 4 is a view in vertical section through the device, taken substantially on the line 4—4 of Figure 2.

Figure 5 is a detail view in perspective of the ash tray and match holder.

Figure 6 is a detail view in perspective of the bracket.

Figure 7 is a detail view in front elevation of the clamp.

Figure 8 is a detail view in top plan of the clamp.

Referring now to the drawings in detail, it will be seen that the embodiment of the invention which has been illustrated comprises an angular bracket which is designated generally by the reference numeral 1, said bracket including a vertical back plate 2 and a horizontally extending tray supporting plate 3. Projecting at right an-

gles from the top of the back plate 2 are spaced fingers 4 for engagement with the top of a table or other support. Struck out from the lower portion of the back plate 2 in a manner to constitute an extension of the tray supporting plate 3 is an apertured guide 5, the purpose of which will be presently set forth. The tray supporting plate 3 is formed to provide a pair of spaced, parallel arms 6. A portion of the material of the plate 3 which is struck out to form the spaced arms 6 is bent upwardly, as at 7, to provide, in conjunction with said plate 3 and the back plate 2, a cigarette holder. A conventional package of cigarettes may be placed in the holder thus provided or, if desired, loose cigarettes may be placed therein. The member 6 has formed in its upper portion a slot 8.

Slidably mounted on the back plate 2 of the bracket 1 is a clamp 9 which includes a depending stem 10 which is slidably engaged in the guide 5. A coil spring 11 encircles the stem 10 and has one end engaged with the guide 5 and its other end engaged with the clamp 9 for yieldingly urging said clamp into engagement with the table or other support. The clamp 9 further includes thumb receiving side wings or members 12 through the medium of which said clamp may be conveniently depressed against the tension of the spring 11. The reference numeral 13 designates notches in the forward portion of the clamp 9 which slidably receive the vertical marginal portions of the back plate 2 for mounting said clamp thereon.

The clamp 9 still further includes upstanding lugs 14 for engagement behind the usual apron 15 of a card table top 16, as best seen in Figure 1 of the drawings. Also rising from the clamp 9, at the rear thereof, is a flange 17 which, together with the lugs 14, is engageable beneath the top 18 of a table of the type suggested in Figure 3 of the drawings. Of course, the device may be mounted on any other support for which it may be found adapted.

The reference numeral 19 designates an ash tray which is removably mounted beneath the plate 3 of the bracket 1. The tray 19 is provided, on its sides, with integral hooks 20 which are slidably engageable with the plate 3 for removably mounting said tray therebeneath. Depending from the tray 19 is a match holder 21 having a lower end portion 22 formed for engagement in a conventional match box. If desired, a match holder may be provided on both sides of the tray 19.

In use, when the device is to be mounted on

a card table, the clamp 9 is depressed against the tension of the spring 11 by engaging the thumbs on the portions 12. The lugs 14 are then engaged behind the depending apron 15 of the card table after which the fingers 4 are swung over the top of said table. The clamp 9 is then released and the spring 11 is thus permitted to function to cause said clamp 9 to co-act with the fingers 4 for firmly securing the device to the table. When the device is to be mounted on a table of the type shown in Figure 3 of the drawings, or on a substantially similar support, the lugs 14 and the flange 17 engage beneath the top thereof, as is believed to be apparent. 10
15 Of course, to remove the device it is only necessary to depress the clamp 9 sufficiently against the tension of the coil spring 11. As is also believed to be apparent, the tray 19 may be conveniently removed for emptying by simply slipping said tray off the supporting plate 3 of the bracket 1. An extension 23 rises from the back plate 2 of the bracket 1 for concealing the shank 10 of the clamp 9 when the device is removed from the table. 20
25 It is believed that the many advantages of a smoker's appliance constructed in accordance with the present invention will be readily understood, and although a preferred embodiment of the invention is as illustrated and described, 30 it is to be understood that changes in the details of construction and in the combination and arrangement of parts may be resorted to which will fall within the scope of the invention as claimed.
35 What is claimed is:—

1. A smoker's appliance of the class described comprising an angular bracket including a vertical back plate and a horizontal supporting plate, a spring actuated clamp slidably mounted on

the back plate for removably mounting the bracket on a support, and a removable ash tray slidably mounted on the supporting plate.

2. A smoker's appliance of the class described comprising an angular bracket including a vertical plate and a horizontal plate, fingers on the upper end of the vertical plate engageable on a support, a removable ash tray slidably mounted on the horizontal plate, a tongue struck up from the horizontal plate and providing, in conjunction with said horizontal plate and vertical plate, a cigarette holder, and a spring actuated clamp slidably mounted on the vertical plate and engageable beneath the support. 5 10

3. A smoker's appliance of the class described comprising an angular bracket including a vertical plate and a horizontal plate, a spring actuated clamp on the vertical plate engageable with a support, a tongue rising from the horizontal plate and providing, in conjunction with said horizontal plate and vertical plate, a cigarette holder, a removable ash tray slidably mounted on the horizontal plate, and a match holder depending from the ash tray. 15 20

4. A smoker's appliance of the class described comprising an angular bracket including a vertical plate, a horizontal plate, and a rearwardly projecting apertured guide, fingers on the upper end of the vertical plate engageable on a support, a spring actuated clamp slidably mounted 30 on the vertical plate and engageable beneath the support, a depending stem on the clamp slidably engaged in the guide, a removable ash tray slidably mounted on the horizontal plate, and a match holder depending from the ash tray. 25 35
